UNITED STATES PATENT OFFICE.

WILLIAM F. HENDRY, OF OSSINING, NEW YORK, ASSIGNOR, BY MESNE ASSIGNMENTS, TO NATIONAL CARBON COMPANY, INC., OF NEW YORK, N. Y., A CORPORATION OF NEW YORK.

DRY CELL.

Application filed January 23, 1924. Serial No. 688,057.

This invention relates to dry cells and it to form an adherent coating thereon. In 55 accordance with a further feature of the invention the bibulous material is applied together with the paste, which may consist of flour, starch or the like.

5 Two general types of dry cells are in general commercial use; the so-called paper lined and the bag type cells. In the former the bibulous lining is usually provided in the form of a sheet of paper coated with 10 paste which is placed against the inside of a zinc container electrode. This lining serves physically to separate the depolarizing mixture from the anode without interference with the electrolytic action. Usually, 15 the depolarizing mixture is tamped in the lined zinc can and then the paper is turned down and the cell is sealed. In the bag type cell a bobbin, i. e., the depolarizing mixture molded around a central carbon electrode, is 20 enveloped in a wrapping of cellulose material (cotton, paper or the like). This bobbin, with its bibulous wrapper, is placed within a slightly larger zinc container electrode. While the bobbin is centrally held 25 within the electrode, paste is poured into the container, filling up the space between the bobbin and the zinc anode.

The objections to both methods are manifold. In the paper lined cell the coating of 30 the paper sheets and the inserting of the paper in the cans are relatively expensive operations. Furthermore, the paper is liable to be injured while the depolarizing mixture is being tamped or is otherwise being inserted into the container. It has been suggested to apply the paste direct to the zinc 35 can; however, this does not materially decrease the speed at which the cells may be assembled. In the assembly of the bag type

40 cells complicated and expensive machinery is required to center the bobbin while the paste is being poured into the container and around the bobbin, because otherwise the separating lining would not be uniform 45 throughout the circumference of the cell. Furthermore, the provision of the bibulous material around the bobbin also entailed considerable expense.

It is the object of the present invention to 50 obviate some of the drawbacks incident to the assembly of bag type and paper lined dry cells by applying the bibulous material, preferably in a comminuted form, direct to the mass of depolarizing material and cause

The important steps of the process are illustrated in the drawing in which 2 is a shaft carrying tablets 1 compacted of depolarizing material and separated from each other by means of spacers 3. The tablets are caused to rotate and move in the direction of their axes in front of a sprayer 4 through which a mixture 5 of the above described composition, and contained in a vessel 6, will be applied around the tablets. The tablets rotate and pass in front of a hot air blast 7, so as to accelerate the drying of the coat. Instead of the arrangement herein disclosed the tablets may be coated also to form a homogeneous mass like a bobbin, in which case the spacers need not be provided, a sufficient number of tablets being coated together to permit their insertion into a zinc cup.

Obviously, the same method or methods

may be used to coat bobbins of the conventional type, whereby the necessity of providing muslin bags or the like will be obviated.

- 5 When the washers 1 are to be used to make up multiple zinc electrode batteries such as are described in my copending application Serial No. 654,613, filed July 30, 1923, and Serial No. 688,058, filed Jan. 23, 1924, then 10 the separators 3 are omitted and the washers are spaced on shaft 2 so as to insure the covering of the entire surface of washers 1 with the mixture 5.

What I claim is:

- 15 1. The method of making dry cells which consists in compacting the depolarizing mixture into tablets, applying to said tablets a coating composed of granulated wood pulp,

flour, zinc chlorid and water, drying the coating, placing the coated tablets in a zinc 20 container electrode, and passing a carbon electrode through said tablets.

2. The method of making dry cells which consists in compacting the depolarizing mixture into tablets, rotating said tablets and 25 displacing them in the direction of their axes first in front of a spray of granulated wood pulp, flour, zinc chlorid and water and then in front of a blast of heated air, placing the coated tablets in a zinc electrode, 30 and passing a carbon electrode through said tablets.

In testimony whereof, I have signed my name to this specification, this 22nd day of January, 1924.

WILLIAM F. HENDRY.
